UNITED STATES PATENT OFFICE.

WALTER W. CHRISTENSEN, OF CHICAGO, ILLINOIS.

RECEPTACLE-CLOSURE.

No. 836,090.

Specification of Letters Patent.

Patented Nov. 20, 1906.

Application filed March 8, 1906. Serial No. 304,922.

To all whom it may concern:

Be it known that I, WALTER W. CHRISTENSEN, a citizen of the United States, residing at Chicago, in the county of Cook and State of Illinois, have invented certain new and useful Improvements in Receptacle-Closures; and I do hereby declare the following to be a full, clear, and exact description of the invention, such as will enable others skilled in the art to which it appertains to make and use the same.

My invention relates to a novel construction in a receptacle-closure designed mainly for large-necked bottles, such as milk-bottles, vaseline-bottles, and for jars such as are used by druggists and others, the object being to provide cheap and efficient means for hermetically sealing such receptacle and to provide means for readily removing the sealing medium without the use of tools of any description and without injury of any kind to said sealing medium; and it consists in the features of construction and combinations of parts hereinafter fully described and claimed.

In the accompanying drawings, illustrating my invention, Figure 1 is a top plan view of a receptacle-closure constructed in accordance with my invention. Fig. 2 is a central vertical section of the same on the line 2 of Fig. 1. Fig. 3 is a diagrammatic view showing the method of determining the shape of the mouth portions of receptacles to best adapt the same for my purposes.

My said invention comprises two parts, each of which coacts with and is dependent upon the other to hermetically seal a bottle or other receptacle, said parts comprising the mouth portion A of the receptacle, which is formed as hereinafter more particularly described, and a circular disk B, which may be made of cork, paper, or any other suitable material. The said mouth portion A of the receptacle is very slightly flaring, the degree of taper of the inner wall thereof being suitably determined, as shown in Fig. 3, in which D is a line indicating the plane of the upper end of said tapered inner wall, E is an arc of radius equal to the largest radius of said tapered inner wall and having its center at F in said plane D, and G is a cord intersecting said arc in the plane D and approximately fifteen to twenty degrees below the latter, said cord G indicating the inner wall of said mouth portion. The said arc E indicates, substantially, the line of travel of the outermost edge of the disk when turned as indicated in dot-

ted lines in Fig. 2, and it will be apparent that when so turned the raised edge will be forced upwardly and slightly laterally. The taper is thus rendered sufficient to prevent said disk B from being readily forced through said mouth portion and is at the same time so slight as to obtain an excellent frictional hold upon the edge of said disk, so that the latter will be firmly held therein. The said disk may be thin or relatively heavy—that is to say, such thickness should exceed one-eighth to one-sixth the radius thereof, said radius being coincident with the largest radius of said tapered inner wall. The receptacle is sealed by forcing the disk into said mouth A thereof to a depth preferably such that the upper face of said disk lies in or slightly below the plane of the upper edge of said tapered inner wall. To open said receptacle, it is only necessary to press on said disk with the finger adjacent its periphery, whereby it will be canted, as indicated in dotted lines, Fig. 2, turning on approximately diametrically oppositely disposed fulcrums, which by reason of the taper of said inner wall, however, are not fixed, but will change their positions on the periphery of said disk as the cant thereof is increased or decreased. When the point in the periphery opposite the point at which pressure is applied has been raised sufficiently to permit the same to be easily grasped, it is removed and may be easily replaced at will.

My said closure is well suited for milk-bottles, being more sanitary by reason of the absence of the shoulder on which the disks of bottles at present used are seated, and consequently of the dirt-collecting corner afforded thereby.

The rim H of the mouth of said receptacle may be and preferably is threaded externally to receive a screw-cap J, adapted to protect the disk against accidental injury or removal in shipment or handling and is designed to be employed on receptacles containing hospital supplies or other substances, as such packages are frequently long in stock and handled a great deal. Said disk is preferably made of cardboard and is coated with paraffin, beeswax, or the like to render it moisture-proof.

I claim as my invention—

1. A receptacle-closure comprising in combination the mouth portion of the receptacle having a conically-tapered inner wall converging at its lower end, and a disk corre-

sponding in diameter substantially with the greatest diameter of said tapered inner wall, and adapted when pressure is applied thereto adjacent its periphery at one point, to be canted.

2. A receptacle - closure comprising the mouth portion of the receptacle having a conical inner wall converging at its lower end, and a disk of relatively yielding material corresponding in diameter substantially with the greatest diameter of said conical inner wall of said mouth portion and adapted to be forced into the latter and be held frictionally in place therein, said disk being adapted to be canted by applying pressure thereon at a point adjacent its periphery.

3. A receptacle - closure comprising the mouth portion of the receptacle having a

conical inner wall converging at its lower end and a disk of relatively yielding material, having a greater diameter than the smallest diameter of said tapered inner wall and adapted to be forced into said mouth and held frictionally in place therein, said disk being adapted to be turned on fulcrums disposed at substantially opposite points in its periphery upon applying pressure upon said disk at a point adjacent its periphery.

In testimony whereof I have signed my name in presence of two subscribing witnesses.

WALTER W. CHRISTENSEN.
